INVENTOR
ERASMIUS RAUS.

BY H. T. Fisher, Atty

UNITED STATES PATENT OFFICE.

ERASMUS RAUS, OF CLEVELAND, OHIO.

CALIPERS.

SPECIFICATION forming part of Letters Patent No. 672,493, dated April 23, 1901.

Application filed November 10, 1900. Serial No. 36,031. (No model.)

To all whom it may concern:

Be it known that I, ERASMUS RAUS, a citizen of the United States, residing at Cleveland, in the county of Cuyahoga and State of Ohio, have invented certain new and useful Improvements in Calipers; and I do declare that the following is a full, clear, and exact description of the invention, which will enable others skilled in the art to which it appertains to make and use the same.

My invention relates to calipers; and the object of the invention is to provide an instrument for taking the exact diameter of internally-threaded objects of whatever kind—as, for example, the diameter of a nut, as shown in the accompanying drawings, the diameter of a threaded pipe, tube, or other article.

To these ends the invention consists in the construction, combination, and arrangement of parts, substantially as shown and described, and particularly pointed out in the claims.

In the accompanying drawings, Figure 1 is a plain elevation of my new style of calipers and a cross-section of a nut to show their use. Fig. 2 is an edge elevation of the calipers alone, and Fig. 3 is a perspective view of the adjusting-bracket designed to set the device at any desired adjustment.

The instrument thus shown comprises, first of all, two similar and equal side bars A and B, having teeth 3 and 4 at their respective ends on their outer edges, the said ends being each offset inward at their extremities, substantially as shown, to enable the smallest diameters possible to be measured and at the same time afford room between said bars for the connecting and operating parts. The plan on which the device is constructed and operates contemplates the connection of bars A and B in parallel lines laterally adjustable in respect to each other and also lengthwise adjustable one to the other at least the full measure of the pitch of the thread to be gaged and as will hereinafter more fully appear. To these several ends an arm C is affixed rigidly to bar A and extends across bar B and beyond the same some distance, so as to accommodate the widest possible lateral adjustment of said bars, substantially as shown in dotted lines in Fig. 1. Two sets of toggle-links 5 and 6, respectively, connect side bars A and

B and are connected at their inner ends with the ends of connecting-bar D. Said bar D is parallel to and centrally between side bars A and B and is the immediate member through which the links 5 and 6 are controlled and held rigidly at any adjustment. To this end also I employ a spiral spring 7, wound spirally about bar D and bearing at its ends against collars on said bar. The lower of these collars especially is adapted to slide on bar D, and its constant tension is exerted to spread the device and throw bars A and B apart, so that the device will spread wide open through said spring, if it be not held or locked. Then also to operate it the side bars are gripped between the fingers and pressed toward each other against the tension of the spring and in taking measurements are locked when the desired measurement has been made. Now to effect this locking I employ in this instance a bracket E, Fig. 3, constructed at 10 to slide on arm C and provided with a set-nut 12 to fasten it. By this means an approximate measurement may be made without special care. Then to get the finer measurement and to fix the device therat I employ a set-nut 13 higher up. This nut also passes through bracket E and bears against the edge of bar B. The counter-pressure on said bar is from spring 7, so that bar B will hold its place when once adjusted by these means; but there is also a third adjustment wanted to measure the pitch of the thread as well, and this is obtained through screw 14 at the top in the right-angled extremity of bracket E. This screw bears on a lug or projection 15 on arm B, holding it down, while keeper 16 on said bar, bearing on arm, takes the pressure in that direction. This makes a rigid construction and locks all the said parts together when said several screws are tightened. Of course I regard this rather one of several ways in which these adjustments may be effected, and hence I regard my invention as broad as any and all equivalents of what I here show and describe.

The adjustment for pitch referred to is seen in Fig. 1, where a nut G is shown as the object to be gaged. In this case the device would be spread to the width of the diameter approximately and set by thumb-screw 12. Then the finer adjustment would be by screw

13 and the pitch adjusted or fixed by screw 14. This done the device would be removed from the nut by simply compressing it in the hand enough to release teeth 3 from the 5 threads, and then all the parts would resume or go back to the place at which the several nuts fixed them and remain there until the bolt, tube, pipe, or other article for which the measurements were taken had the size of bore 10 and pitch of thread given thereto, thus matching said part accurately with confidence that it will fit and work as designed.

If preferred, one set of the teeth 3 and 4 may be omitted, in which case the side measuring-bars A and B would not extend beyond 15 the links at that end.

The keeper 16 serves especially to hold bar B and arm C closely together and is deep enough lengthwise to allow bar B to be depressed in respect to arm C, as seen in dotted lines, Fig. 1.

The offset or shoulder whereby either extremities 17 or 18 are formed is of such depth as to enable the link-connecting bar to lie between 25 said bars when the extremities at either or both ends are brought against each other. The toggle-links overlap the middle bar, so that they do not fold between the side bars.

What I claim is—

30 1. In calipers, a set of side measuring-bars having teeth at their ends to engage in threads, link mechanism connecting said bars constructed and arranged to hold the bars parallel at all times, a rigid member on one of said bars, and means on the other bar adjustably connected with said member to provide both a lateral and vertical adjustment of said bars, substantially as described.

2. In calipers, a set of side measuring-bars, 40 two sets of links of equal length, and a central bar uniting the said side bars, a cross-arm on one of said measuring-bars and a spring about the central bar bearing on said arm, whereby the device is spread apart, substantially as described.

45 3. The two side bars with teeth at their ends outside, two sets of links of equal length connecting said bars, a central bar uniting the

inner ends of said links, a cross-arm rigid with one of said side bars and slidably engaged with the other side bar, and a spring to spread the device, substantially as described. 50

4. The side bars and the mechanism pivotally connecting them in parallel lines, a transverse arm rigid with one of said bars and 55 slidably connected with the other bar, and means on said arm to adjust said bars in relation to each other and the work to be measured, substantially as described.

5. A set of thread-measuring bars and 60 means connecting said bars constructed to hold them in movable parallel relation, a transverse member on one of said bars, and means adjustably mounted on said member to set said bars in parallel relation and to allow 65 one bar to be lengthwise adjusted in respect to the other bar, substantially as described.

6. The two side measuring-bars and the link connections for holding them parallel, a transverse arm on one of said bars, a projection and keeper on said other bar, and means to engage said arm and projection to adjust and set said bars in distance and lengthwise adjustment relation with each other, substantially as described. 70

7. The side bars and the toggle mechanism connecting them, a cross-arm rigid with one of said bars and having a slideable connection with the other bar, a bracket adjustable on said arm outside the free side bar, and a set-screw on said bracket to determine the lateral adjustments of said bars, substantially as described. 75

8. The device having side measuring-bars and means to hold them parallel, a transverse 85 arm connected with said bars and a bracket adjustable on said arm and provided with screws to fix said device in all its adjustments, substantially as described.

Witness my hand to the foregoing specification this 31st day of October, 1900. 90

ERASMIUS RAUS.
